United States Patent

Des. 236,117
Patented July 29, 1975

236,117

PORABLE URINAL

Luther Elkins, 13031 Forest Drive,
Bowie, Md. 20716

Filed Aug. 16, 1973, Ser. No. 388,904

Term of patent 14 years

Int. Cl. D23—02

U.S. Cl. D23—48

Fig. 2.

Fig. 3.

Fig. 6.

Fig. 7.

Fig. 8.

Fig. 11.

Fig. 12.

Fig. 13.

Fig. 14.

Fig. 15.

FIG. 17.

FIG. 18.

FIG. 19.

FIG. 20.

FIG. 1 is a plan view of a portable urinal embodying my new design;

FIG. 2 is a front view thereof;

FIG. 3 is a rear view thereof;

FIG. 4 is a right side view thereof;

FIG. 5 is a left side view thereof;

FIG. 6 is a plan view of a modified form of the portable urinal shown in FIG. 1;

FIG. 7 is a front view of FIG. 6;

FIG. 8 is a rear view of FIG. 6;

FIG. 9 is a right side view of FIG. 6;

FIG. 10 is a left side view of FIG. 6;

FIG. 11 is a plan view of a second modified form of the portable urinal shown in FIG. 1;

FIG. 12 is a front view of FIG. 11;

FIG. 13 is a rear view of FIG. 11;

FIG. 14 is a right side view of FIG. 11;

FIG. 15 is a left side view of FIG. 11;

FIG. 16 is a plan view of a third modified form of the portable urinal shown in FIG. 1;

FIG. 17 is a front view of FIG. 16;

FIG. 18 is a rear view of FIG. 16;

FIG. 19 is a right side view of FIG. 16; and

FIG. 20 is a left side view of FIG. 16.

I claim:

The ornamental design for a portable urinal, substantially as shown and described.
